UNITED STATES PATENT OFFICE

FREDERICK E. TERMAN, OF STANFORD UNIVERSITY, CALIFORNIA, ASSIGNOR TO WIRED
RADIO, INC., OF NEW YORK, N. Y., A CORPORATION OF DELAWARE

OSCILLATION SYSTEM

Application filed November 19, 1929. Serial No. 408,391.

My invention relates broadly to electron tube oscillators, and more particularly to an arrangement of circuit for electron tube oscillators for producing sustained electrical oscillations.

One of the objects of my invention is to provide an electron tube circuit arrangement for an oscillation system in which sustained oscillations at constant frequency may be produced and wherein the plate electrode is maintained at high negative potential.

Another object of my invention is to provide a circuit arrangement for an electron tube oscillator in which a voltage reducing reaction exists between the plate circuit and the grid circuit for establishing oscillations of constant frequency.

Still another object of my invention is to provide a circuit arrangement for an electron tube oscillator, wherein the plate and grid circuits are connected in such manner that a reduction in voltage occurs between the input and output circuits in the course of the feed-back operation of the electron tube circuits for the production of constant frequency oscillations.

A further object of my invention is to provide a circuit for a piezo electric crystal controlled oscillator, wherein the piezo electric crystal element ground to a predetermined frequency characteristic is connected between the cathode and plate electrodes of the electron tube system and an oscillator circuit connected between the cathode and grid electrodes of the oscillator system for the production of constant frequency oscillations.

Other and further objects of my invention will be more fully understood from the specification hereinafter following by reference to the accompanying drawing in which:

Figure 1 is a diagrammatic illustration of a simplified form of the oscillator circuit of my invention; and Fig. 2 shows a circuit arrangement embodying the principles of my invention in which the oscillations produced in the electron tube circuits are sustained at constant frequency by means of a piezo electric crystal element.

In the oscillator system of my invention I

employ an electron tube connected in an inverted manner by which the electron tube may function as an oscillator. I employ the principles set forth more fully in my application entitled Electron tube circuit, Serial No. 405,363 filed November 7, 1929. A voltage reducing action is obtained between the plate and grid circuits of the oscillator system in the manner set forth in the aforesaid application. The plate portion of the inductance which may be common to the plate and grid circuits is therefore many times greater than the grid portion of the inductance. I have found that a ratio of 8 to 1 between the inductance in the plate and the inductance in the grid circuit is a desirable proportion when using a UX 171A tube. A high negative potential is impressed upon the plate electrode and a positive potential applied to the grid electrode. The ability of the inverted electron tube to oscillate depends upon the reflex mutual conductance. The higher this value, the easier it is for oscillations to take place. The circuit arrangement of my invention is particularly adapted for operation under control of a piezo electric crystal system, and when the circuit is piezo electrically controlled the piezo electric crystal element is connected between the plate and cathode electrodes, as will be more fully described hereinafter.

Referring to the drawing in more detail, reference character 1 designates the electron tube employed in the circuit of my invention where the tube includes cathode 2, grid 3 and plate 4. The cathode is suitably heated from any desired source such as battery system 5, regulated through resistor 6. The input circuit to the oscillator includes the high potential source 7 having its negative potential connected to plate electrode 4, and its positive terminal connected to the output circuit end 8 of inductance 9. A tap 10 connects to the cathode 2 at a position along the inductance 9 where a larger number of turns are included in the output circuit than are included in the input circuit as represented at 11. The input circuit includes the portion 11 of inductance 9 and the source of potential 12 having its positive terminal connected

to grid electrode 3. The inductance 9 has its terminal ends 8 and 14 bridged by means of condenser 15. For the best conditions of operation I have found that with a positive potential of 66 volts on the grid 3 and a negative potential of 152 volts on the plate when using a CX-371 tube, an oscillating current of 200 milliamperes at approximately 36 kilocycles was obtained in a low resistance circuit at constant frequency.

In Fig. 2 I have shown the method employed for constant frequency control utilizing a piezo electric crystal element 16 connected between electrodes 17 and 18 to the input circuit of the oscillator across plate electrode 4 and cathode 2. The plate 4 is negatively biased from battery 7 through resistance 19. The output circuit in the piezo electric crystal controlled oscillator may include the adjustably tuned system 19 constituted by inductance 20 and variable condenser 21. I have found that the circuit arrangement of my invention operates as an oscillator for the production of oscillations of extremely constant frequency.

While I have described certain preferred embodiments of my invention, I desire that it be understood that modifications may be made and that no limitations upon my invention are intended other than are imposed by the scope of the appended claims.

What I claim as new and desire to secure by Letters Patent of the United States is as follows:

35. 1. An oscillation system comprising an electron tube including a cathode, a grid and a plate, an input circuit including said plate and cathode, an output circuit including said grid and cathode, means for charging said anode at a negative potential, means for charging said grid at a positive potential, and a frequency determining vibratile element connected in said input circuit.

40. 2. An oscillation system comprising an electron tube having a cathode, a grid and a plate, an input circuit interconnecting said plate and cathode, an output circuit interconnecting said grid and cathode, means in said output circuit for charging said grid at positive potential, means in said input circuit for charging said plate at negative potential, an inductance connected in said output circuit, and a frequency controlling vibratile element connected in said input circuit for the production of oscillations at constant frequency.

In testimony whereof I affix my signature.
FREDERICK E. TERMAN.
